Nathan Dyer.

8905 X Letters Patent

The schedule referred to in these Letters Patent and making part of the same, containing a description in the words of the said Nathan Dyer himself of his improvement in the mode of making or manufacturing Boots by an instrument called the Hinge Boot Clamp.

It all to whom these presents shall come.

Be it known that Nathan Dyer, of Lebanonburg in the County of Gallia, and State of Vermont, have invented a new and useful improvement in the mode of making or manufacturing Boots by an instrument called "The Hinge Boot Clamp" and that the following is a full and exact description thereof viz. The main part of the "Hinge Boot Clamp" is formed of hard wood or other suitable material of an inch in thickness more or less & of sufficient depth for the front of the Boot. The foot and leg being united by a joint where the human foot and leg are. This joint may be constructed by a semicircular concavity or convexity in the leg or foot, and the reverse in the other; or about the place for the ankle joint. There may be a concavity in one part to be inserted as a tongue in a concavity of the other part and fastened by a pin passing the centre of the arc of the circle forming said joint, or instead of the above mode a metallic plate with suitable shanks or other fastenings may be inserted, or said joint may be made in any manner now known or to be invented if the foot is another joint formed to cover the foot in two parts to be together for the purpose of inserting a wedge or to be operated upon by a screw or lever to assist in the clamping, where the power hereinafter named shall be put in operation. This wedge may be wedges or other fastenings to match grooves or other suitable places in the clamp to prevent it from slipping while the instrument operates.

The

The foot part of said hinge boot clamp is on either side chamfered nearly to the edge - on the bottom of the foot may be inlaid a plate of metallic or other hard substance for a screw which is after named to fit against, also a heel the heel is a plate of iron or other metal in which is fastened the end of a screw which operates as a buckle at that point - In the lower part of the back of said clamp is a cut equal in depth to a plate of iron or other metal, which is attached to said clamp by the last named screw, upon the bottom of the foot and back of the leg having in it a joint near the heel where it is fastened and loose at other end with screws at each end so the said iron is in to force said foot and leg into their proper places and keep said iron outwards which will operate upon the leather as wished for. but the back part of said clamp is a groove in the cut in which is inserted a tongue or latch to keep the clamp erect when placed so - and also to serve for a bed piece for the screw in that part of the instrument to operate against with out injury. The screws may be made of iron or other metallic or glass instrument may be made of metallic, soldered, or of wood or stone, or of any durable material of which it is capable of being made. The foregoing is substantially a description of the instrument. Its peculiar utility and improvement is shown in its application to use. Having suitably blocked out the leather to be clamped - then the leg and foot of the clamp by means of the hinge as near as may be in a straight line, fasten the leather around it in the proper place by slightly sewing the opposite edges then twice the leg and latch it, insert the wedge at the toe then by turning the screws on the bottom of the foot at the heel and back - the leather to be clamped will be immediately compressed into the desired shape. In testimony whereof and that the above is a true specification of my said improvement as above described I have caused to be my hands and seal this 22nd day of April 1835
